DESIGN FOR AN EMBROIDERED LACE YOKE

Herman Kaufman, New York, N. Y.

Application January 31, 1947, Serial No. 136,563

Term of patent 7 years

(Cl. D3—9)

To all whom it may concern:

Be it known that I, Herman Kaufman, a citizen of the United States of America, residing in New York city, county of New York, and State of New York, have invented a new, original, and ornamental Design for an Embroidered Lace Yoke, of which the following is a specification, reference being had to the accompanying drawing, forming part thereof, wherein,

The figure is a plan view of an embroidered lace yoke showing my new design.

The embroidered lace yoke is shown against a black background to bring out the details of the design.

I claim:

The ornamental design for an embroidered lace yoke, substantially as shown and described.

HERMAN KAUFMAN.
